UNITED STATES PATENT OFFICE.

PAUL O. KEPELMAN, OF READING, PENNSYLVANIA.

SUPPLY-VALVE.

1,220,427.

Specification of Letters Patent. Patented Mar. 27, 1917.

Application filed December 6, 1916. Serial No. 135,299.

To all whom it may concern:

Be it known that I, PAUL O. KEPELMAN, a citizen of the United States, residing at Reading, in the county of Berks and State of Pennsylvania, have invented certain new and useful Improvements in Supply-Valves, of which the following is a specification.

This invention relates to improvements in supply valves and it pertains more particularly to valves of this character as applied to flush tanks for water closets.

In valves of this character when used in flush tanks, the opening and closing of the valve is accomplished through the medium of a float whose movement is responsive to the rise and fall of the water in the tank, and a compound lever carrying the valve.

In actual practice it has been found that the valve seat wears away or becomes imperfect through use and it then becomes necessary to disconnect the entire fitting and replace the valve casing base on which the seat is formed.

It is my object in the present instance to avoid this work and its attendant expense, and to this end I have devised a valve casing base member provided with a plurality of easily removable valve seats, nested one in another so that when one becomes useless it may be easily removed and the next succeeding seat may be utilized.

In conjunction with these removable valve seats, I have found it necessary to make provision for suitably adjusting the valve, so that it may be readily accommodated to seat on a lower seat member when one is removed.

The invention is more fully described in the following specification and clearly illustrated in the accompanying drawing, in which I have shown a vertical, central, sectional view of a device containing my invention.

In the said drawing:—

The numeral 1 designates the valve casing and 2 the valve casing base, both of which are of the usual construction.

The base is formed as usual with a valve seat 3 and into this base, and seating on the valve seat, I provide a nest comprising two or more removable, hollow, screw-threaded plugs, 4, each of which is formed with a valve seat 5 on its upper surface and each of which is screwed into the one below it as the lowermost one is screwed into the valve casing base.

The numeral 6 designates the valve,

formed with the usual contacting washer or surface 7 at its lower extremity, and adapted to move vertically in the casing, in the usual manner.

To the upper extremity of this valve I form a rod 8 provided with a series of equidistant perforations 9.

The numeral 10 designates the compound lever, which is also of the usual construction, and which carries the float 15, through the rise and fall of which the lever is operated to actuate the valve 6.

The lower member of this compound lever, 10', is formed with the usual perforation 70 through which it is pivotally attached to the valve plunger, and the numeral 11 designates a removable pivot pin for so attaching it.

When the parts are assembled as shown 75 in the drawing, the rise and fall of the float will cause the valve to seat on the uppermost valve seat 5 and to rise therefrom sufficiently to allow the flow of water through the casing and out of the side outlet 13 to the tank. 80

When this valve seat becomes useless, the casing is removed from the base and the upper valve seat member is removed from the nest, permitting the next succeeding valve seat member to be utilized.

This removal however will require adjustment of the valve so that it will seat properly when the valve is lowered, and this adjustment is easily and rapidly accomplished by merely removing the pin 11, placing the perforation in the lever member 10' in register with the next upper perforation 9 in the valve plunger and replacing the pin. This will lower the valve a distance equal to the distance between the valve seats 5 of two 95 connected valve seat members and the valve will seat as before.

When the entire nest of valve seat members have been used, and the last one is removed, the valve may seat on the valve seat 100 3 of the base member as usual, and the valve plunger will then be pivoted to the lever 10' at its uppermost perforation. When this valve seat 3 becomes useless, it will not even then become necessary to remove it, but a 105 new nest of removable valve seats may be placed in position, and thereafter the removable valve seats only may be utilized, but the base member will continue to do service in all senses except that as a valve seat it 110 will be useless.

It is evident that with this construction,

the life of the device will not only be materially prolonged, but that leaking valves may be easily and rapidly overcome and this by unskilled hands, thus overcoming delay, annoyance, and expense incidental to the plumber's visit.

Having thus fully described my invention, what I claim and desire to secure by Letters Patent is:—

- 10 1. In a supply valve, the combination of a valve casing, a valve casing base provided with a valve seat, a nest of removable valve seat members, a movable valve provided with a rod, said rod having a series of perforations to accommodate the valve to the respective seats, a compound lever for actuating the valve and means selectively engageable in said perforations for adjustably attaching the valve rod to the lever.
- 15 2. In a supply valve of the character described, the combination of a casing, a verti-

cally movable valve therein, a valve rod formed integrally with the valve, said rod having a series of equi-distant perforations, a compound lever attached to the casing, a float carried by said lever, one of the lever members having a perforation adapted for registration with any one of the perforations in the valve rod, a removable pin inserted in said registering perforations for temporarily attaching the valve rod to said lever member, a casing base member formed with a valve seat, and a plurality of removable valve seat members in nested form, carried by said base member, the valve seats being adapted for successive coaction with the valve upon the successive removal of the valve seats and the successive adjustment of said lever member relative to said rod.

In testimony whereof I affix my signature. 40

PAUL O. KEPPELMAN.
